UNITED STATES PATENT OFFICE

WELLBY ALLEN BRACKETT AND WILLIAM EDWARD RICHARD, OF EVANSVILLE, INDIANA, ASSIGNORS TO SUNBEAM ELECTRIC MANUFACTURING COMPANY, OF EVANSVILLE, INDIANA, A CORPORATION OF INDIANA

CARBURETOR

Application filed August 8, 1927. Serial No. 211,310.

Our invention relates to carburetors and has particular reference to carburetors that are adapted to be utilized in connection with automatically controlled internal combustion engines, such as prime movers for farm lighting plants and the like.

It is well known to those skilled in the art of internal combustion engines that when a cold engine is to be started, it is necessary to supply a richer fuel mixture thereto than is required for the operation of an engine after the same has attained its normal operating temperature. This is frequently accomplished by "choking" the supply of air to the carburetor. The degree of vacuum created in the carburetor by reason of the operation of the engine is thus increased, and the amount of liquid fuel that is forced into the mixing chamber by external atmospheric pressure is likewise increased. Therefore, the ratio of the amount of fuel to the amount of air is increased.

It is difficult to regulate the fuel mixture automatically where an internal combustion engine is automatically controlled. Our invention contemplates the provision of means for accomplishing such regulation, however, but this regulation is accomplished by varying the rate of fuel supply to the carburetor mixing chamber without varying the rate of air supply.

The principal object of our invention, therefore, is to provide a carburetor comprising means for automatically regulating the ratio of fuel and air to be mixed therein when the engine with which the carburetor is associated is started.

Other objects and advantages of our invention will appear from a consideration of the following detailed description in connection with the accompanying drawings, in which:

Figure 1 is a top plan view of a carburetor embodying my invention;

Fig. 2 is a vertical sectional view taken along the line II—II of Fig. 1;

Fig. 3 is an enlarged fragmentary view in perspective showing the construction of a float stem utilized in the carburetor embodying my invention;

Fig. 4 is a view, partly in elevation and partly in section, taken along the line IV—IV of Fig. 1;

Fig. 5 is a horizontal sectional view taken along the line V—V of Fig. 4; and

Fig. 6 is a fragmentary sectional view taken on a line corresponding to the line IV—IV of Fig. 1 and showing one feature of my invention in modified form.

Referring to the drawings, the carburetor embodying our invention comprises a top portion 5 having a horizontal tubular portion 6 of Venturi form extending thereacross. A reservoir member 7 of cup form is secured to the top portion 5 by screws 8 and contains a float 9 that is secured to a vertical stem 10. The stem 10 extends upwardly in close-fitting relation to an opening 11 in a downwardly extending portion 12 of the top portion 5. The stem 10 is adapted to be actuated vertically in the opening 11 but is so fitted therein as to prevent the leakage of fuel through said opening around the stem.

The opening 11 intersects the Venturi tube 6 at the central portion thereof and is in alignment with a similar opening 13 in the upper wall of the tube 6. An upwardly extending tubular portion 14 of said upper wall is adapted to receive a screw-threaded stop member 15 that is provided at the upper end thereof with a knurled knob 16 whereby the vertical position of the stop member 15 may be manually adjusted. A vertical pin 17 is secured to the upper wall of the tube 6 and engages the periphery of the knob 16 to prevent accidental movement of the stop member 15 due to vibration or other causes. The lower surface of the stop member 15 forms a cavity 18 that is adapted to engage the upper extremity of the stem 10 when the same is actuated upwardly through the openings 11 and 13.

A depression 19 forming a channel in one side of the stem 10 is adapted to register with an inclined passage 20 in the downwardly extending portion 12 of the lower wall of the tube 6. The depression 19 is shown in the drawings as being of rectangular cross-section, but it is obvious that a channel of V-shaped semicircular or any other desired

form of cross-section may be utilized with equal effectiveness. The passage 20 constitutes a conduit extending downwardly and transversely to the upper extremity of a vertical conduit 21 that is secured to the downwardly extending portion 12. The conduit 21 extends from this point downwardly through an aperture 22 in the float 9 to a point relatively close to the bottom of the reservoir 7. A fuel conduit is thus provided from a point near the bottom of the reservoir 7 to the center of the Venturi tube 6, and this conduit is adapted to conduct liquid fuel from the reservoir to the Venturi tube, as will be hereinafter more fully described.

The channel 19 is tapered downwardly along the stem 10, as shown in Figs. 2 and 3, to provide a conduit extending from the upper extremity of the passage 20 to the center of the Venturi tube 6, this conduit having a decreasing cross-sectional areas as the float 9 is raised to raise the stem 10 correspondingly. The position of the stop member 15 is adapted to be adjusted by the knob 16 to limit vertical movement of the stem 10, which, therefore, determines the minimum cross-section of the conduit 19 at the point where this conduit is intersected by the conduit 20.

The Venturi tube 6 is provided at one extremity thereof with a flange portion 23 that is adapted to be secured to the intake manifold of an internal combustion engine by cap-screws 24. A throttle valve 25 is provided in the tube 6 near the extremity thereof adjacent the flange 23 and is adapted to be actuated by a stem 26 and disc or dial 27. An actuating member 28 is operatively connected to the disc or dial 27 to permit actuation of the valve 25 in any desired manner. A pin 29 that is secured to the stem 26 co-operates with two stop-screws 30 and 31 to determine the maximum and minimum openings of the valve 25.

Air is supplied to the Venturi tube 6 through a valve 32 in the extremity of the tube 6 opposite to the extremity in which the throttle valve 25 is disposed. The valve 32 may be adjusted or operated either automatically or manually in any desired manner. Thus, it will be seen that the Venturi tube 6 constitutes a mixing chamber to which liquid fuel may be supplied through the channel conduit 19 in the stem 10 and to which air may be supplied through the valve 32.

The reservoir 7 is adapted to be supplied with liquid fuel through an aperture 33, shown in Fig. 5, to which any suitable pipe or conduit may be connected. Such a pipe or conduit will ordinarily be connected to a fuel pump that is operated whenever the engine with which the carburetor is associated is in operation. Such a fuel pump 65 will take liquid fuel from any suitable tank or

reservoir, which may be disposed below the level of the reservoir 7 of the carburetor if desired. An aperture 34, which also connects with the interior of the reservoir 7, constitutes an overflow conduit for said reservoir and is adapted to be connected by means of a pipe or conduit 35 to the main fuel reservoir to permit drainage of excess fuel from the carburetor reservoir to the main reservoir. The cross-sectional area of the overflow conduit 35 is of such size as to limit the amount of fuel that may be contained within the reservoir 7 to the level at which the aperture 34 connects therewith, which is relatively close to the top of the reservoir. Two apertures 36 and 37 of relatively small cross-sectional area connect the chamber of the reservoir 7 with the aperture 34 at lower levels than that at which the main portion of the aperture 34 connects with the reservoir 7, for a purpose to be described hereinafter.

A vertical rod 38 extends downwardly in close-fitting relation to an aperture 39 through the top portion 5 of the carburetor, and thence in relatively loose-fitting relation through an aperture 40 in the float 9. The lower extremity of the rod 38 is provided with a flange portion 41 of greater diameter than that of the aperture 40 and constitutes a stop or limit to determine the lowermost position of the float within the reservoir 7. The rod 38 is provided with a plurality of indentations or notches 42 near the upper extremity thereof and a resilient member 43 is adapted to co-operate with these notches to maintain the rod 38 in the position in which it is manually set. The resilient member 43 is secured to the top portion 5 of the carburetor by a screw 44. It will be seen that the rod 38 may be manually adjusted to determine the lowermost position of the float 9 as desired and that such adjustment will be maintained by reason of the engagement between one of the notches 42 and the resilient member 43.

When an internal combustion engine with which the carburetor embodying our invention is associated is to be started, such engine may be cranked automatically in response to any desired condition and in any well known manner. The fuel pump associated with the engine is thereupon operated and supplies a quantity of fuel to the reservoir 7 and such fuel is conducted from the bottom of the reservoir 7 through the conduit 21, the passage 20 and the channel 19 to the Venturi tube 6, within which the pressure has been reduced by reason of the cranking of the engine. The float 9 will be in its lowermost position, as determined by the vertical position of the rod 38, and the cross-sectional area of the channel 19 at the point where this channel is intersected by the passage 20 will be relatively large.

Therefore, a relatively large quantity of fuel is admitted to the Venturi tube 6, where it is mixed with the air admitted through the valve 32 to produce a relatively rich mixture. This mixture is supplied to the engine through the throttle valve 25 and the engine will start to operate as soon as combustion takes place therein.

As the reservoir 7 is supplied with additional fuel from the pump, the float 9 is raised to actuate the stem 10 upwardly. The cross-section area of the channel 19 at the point of intersection with the passage 20 is thus gradually decreased to lessen the amount of fuel that is supplied to the mixing chamber within the tube 6. Since the rate of air supply is unchanged, the fuel mixture is leaner, which is the condition desired as the temperature of the engine increases. The rate at which the reservoir 7 is filled with fuel is determined by the size and position of the apertures 36 and 37 through which fuel is permitted to drain back through the overflow conduit 35 to the main reservoir. It is obvious that by varying the number, size and position of the apertures 36 and 37 the length of time required for the fuel pump to fill the reservoir 7 with fuel may be adjusted to any desired value.

When the reservoir 7 is filled with fuel after the predetermined desired time, the float 9 and the stem 10 assume their uppermost positions as determined by the position of the stop member 15. Under this condition, the cross-sectional area of the channel conduit 19 at the point of intersection with the passage 20 is decreased to its minimum value and the fuel mixture is likewise reduced to the minimum desired proportion of the amount of fuel to the amount of air admitted to the mixing chamber within the tube 6. This minimum value may be determined by adjustment of the knob 16 in accordance with temperature conditions, quality of fuel, or any other desired conditions.

The ratio of fuel and air to be supplied to the mixing chamber when the engine is started may be adjusted by adjusting the position of the rod 38. During cold weather, for example, the rod 38 may be set at the lowermost position, as shown in Fig. 4 of the drawings, to permit the greatest possible amount of fuel to be supplied to the mixing chamber within the tube 6 when the engine is started. Under other conditions, the rod 38 may be set at higher positions to decrease the area of the channel conduit 19 at the point of intersection with the passage 20, thereby causing a leaner fuel mixture to be supplied to the engine when the same is started.

The modification shown in Fig. 6 of the drawings, consists in providing an adjust-

able valve member 45 for co-operating with an opening 46 connecting the lower part of the reservoir 7 with the conduit 34. The rate at which the reservoir 7 may be filled may thus be predetermined by adjusting the valve 45 to obtain any desired cross-section of the opening 46.

From the foregoing description it will be seen that we have provided a carburetor comprising means for automatically regulating the ratio of air and fuel in the combustible mixture supplied to an internal combustion engine. The maximum and minimum values of this ratio are readily adjustable independently of each other and the time required for the ratio to be automatically changed from one limit to the other may also be adjusted as desired. An internal combustion engine equipped with a carburetor of this type may therefore be automatically operated under all temperature conditions and with any available quality of fuel.

While we have shown and described only one specific embodiment of our invention, it will be seen that various changes and modifications may be made in the details of structure thereof without departing from the spirit and scope of our invention. Therefore, we desire that our invention be limited only by the prior art and the scope of the appended claims.

We claim as our invention:

1. A carburetor comprising a mixing chamber, means for conducting air and fuel thereto, a fuel reservoir containing a float, and means controlled by the float for decreasing the rate of fuel supply from the reservoir to the mixing chamber when the amount of fuel in the reservoir is increased.

2. A carburetor comprising a mixing chamber, means for conducting air and fuel thereto, a fuel reservoir containing a float, and means controlled by the float for permitting an increase in the rate of fuel supply from the reservoir to the mixing chamber when the amount of fuel in the reservoir is decreased.

3. A carburetor comprising a mixing chamber, a fuel reservoir containing a float, a fuel conduit connecting the fuel reservoir and the mixing chamber, a valve in said conduit the degree of opening of which is decreased by upward movement of the float, and adjustable means for limiting the movement of the float.

4. A carburetor comprising a mixing chamber, a fuel reservoir containing a vertically movable float, a fuel conduit connecting the fuel reservoir and the mixing chamber, a valve in said fuel conduit the degree of opening of which is decreased by upward movement of said float and adjustable means for limiting the upward movement of said float.

5. A carburetor comprising a mixing chamber, a fuel reservoir containing a vertically movable float, a fuel conduit connecting the fuel reservoir and the mixing chamber, a valve in said fuel conduit the degree of opening of which is decreased by upward movement of said float and adjustable means for determining the lowermost position of said float.
6. A carburetor comprising a mixing chamber, a fuel reservoir containing a vertically movable float, a fuel conduit connecting the fuel reservoir and the mixing chamber, a valve in said fuel conduit the degree of opening of which is decreased by upward movement of said float, adjustable means for limiting the upward movement of said float, and adjustable means for determining the lowermost position of said float.
7. A carburetor comprising a mixing chamber, a fuel reservoir beneath said mixing chamber, a vertically movable float in said fuel reservoir, a fuel conduit connecting said fuel reservoir and said mixing chamber and having a vertical portion, a vertical stem for the float extending upwardly through the vertical portion of the fuel conduit and through the mixing chamber and having a channel of varying cross-section therein to control the rate of fuel flow through the fuel conduit in accordance with the position of the float, and an adjustable stop member in the upper wall of the mixing chamber for engaging the upper extremity of the float stem to limit the upward movement of the float.
8. A carburetor comprising a mixing chamber, a fuel reservoir beneath said mixing chamber, a vertically movable float in said fuel reservoir, a fuel conduit connecting said fuel reservoir and said mixing chamber and having a vertical portion, a vertical stem for the float extending upwardly through the vertical portion of the fuel conduit and through the mixing chamber and having a channel of varying cross-section therein to control the rate of fuel flow through the fuel conduit in accordance with the position of the float, and a screw-threaded member co-operating with a screw-threaded opening in the upper wall of the mixing chamber for engaging the upper extremity of the float stem to limit the upward movement of the float.
9. A carburetor comprising a reservoir member of cup form, a cover member therefor having a substantially horizontal hollow cylindrical portion forming a mixing chamber, said cylindrical portion having a vertical passageway and an inclined intersecting passageway in the lower wall thereof, a vertical stem extending through said vertical passageway, a float disposed within the reservoir member and secured to the stem, and a conduit secured to the cover member
- in connection with the inclined passageway therein, extending downwardly through an aperture in the float and opening into the reservoir chamber near the bottom thereof.
10. A carburetor comprising a reservoir member of cup form, a cover member therefor having a substantially horizontal hollow cylindrical portion forming a mixing chamber, said cylindrical portion having a vertical passageway and an inclined intersecting passageway in the lower wall thereof, a vertical stem extending through said vertical passageway, said stem having a channel of varying cross-section therein in register with the inclined passageway to form a conduit extending into the mixing chamber, a float disposed within the reservoir member and secured to the stem, and a conduit secured to the cover member in connection with the inclined passageway therein, extending downwardly through an aperture in the float and opening into the reservoir chamber near the bottom thereof.
11. The method of regulating the ratio of fuel and air to be mixed in a carburetor which consists in decreasing the rate of fuel supply to the mixing chamber when the amount of fuel in the float chamber is increased.
12. In a carburetor, the combination with a mixing chamber, a reservoir adapted to be filled with fuel and containing a float, and means for supplying fuel to the reservoir, of means controlled by the float for decreasing the rate of flow of fuel from the reservoir to the mixing chamber as the amount of fuel in the reservoir is increased, and means for controlling the length of time required to fill the reservoir with fuel.
13. In a carburetor, the combination with a mixing chamber, a reservoir adapted to be filled with fuel and containing a float, and means for supplying fuel to the reservoir, of means controlled by the float for regulating the rate of flow of fuel from the reservoir to the mixing chamber and means comprising an overflow conduit for controlling the length of time required to fill the reservoir with fuel.
14. In a carburetor, the combination with a mixing chamber, a reservoir adapted to be filled with fuel and containing a float, and means for supplying fuel to the reservoir, of means controlled by the float for regulating the rate of flow of fuel from the reservoir to the mixing chamber and an overflow conduit having an opening into the reservoir to limit the amount of fuel that may be contained by the reservoir and another opening into the reservoir to control the length of time required to fill the reservoir with fuel up to said limit.
15. In a carburetor, the combination with a mixing chamber, a reservoir adapted to be filled with fuel and containing a float, and

means for supplying fuel to the reservoir, of means controlled by the float for regulating the rate of flow of fuel from the reservoir to the mixing chamber and an overflow conduit having a relatively large opening into the reservoir near the top thereof to limit the amount of fuel that may be contained by the reservoir and having a plurality of relatively small openings into the reservoir below the level of said relatively large opening to control the length of time required to fill the reservoir with fuel up to the level of said relatively large opening.

10 In witness whereof we have hereunto subscribed our names.
